UNITED STATES PATENT OFFICE.

WILLIAM SOMMER, OF ST. PAUL, MINNESOTA, ASSIGNOR TO AMERICAN HOIST & DERRICK COMPANY, A PARTNERSHIP COMPOSED OF F. J. JOHNSON AND W. O. WASHBURN, OF ST. PAUL, MINNESOTA.

REVERSING MECHANISM FOR HOISTING DRUMS.

Application filed June 30, 1924. Serial No. 723,422.

In the operation of a hoisting apparatus where a winding drum is used to wind up the cable of a bucket or scoop, the weight of the empty bucket is usually relied upon to 5 unwind the cable from the drum when it is disconnected from the winding mechanism. This method of unwinding has frequently proved unsatisfactory, being too slow and it is difficult to utilize the swing of the bucket 10 for the purpose of casting it outwardly at some distance from the end of the supporting boom, the drum offering some little frictional resistance to the pull of the bucket and cable thereon.

15 The object therefore of my invention is to provide a means for reversing or revolving the winding drum backwardly to facilitate the unwinding of the cable therefrom.

20 A further object is to provide a reversing mechanism of simple economical construction which can be applied to the winding drum of a standard hoisting apparatus.

25 The invention consists generally in various constructions and combinations all as hereinafter described and particularly pointed out in the claims.

In the accompanying drawings forming part of this specification,

30 Figure 1 is a sectional view illustrating the application of my invention to the winding drum of a hoisting apparatus;

Figure 2 is a sectional view on the line 2-2 of Figure 1;

35 Figure 3 is a sectional view on the line 3-3 of Figure 1.

Figure 4 is a detail sectional view showing the clutch mechanism connecting the drum with the gear wheel

30 In the drawing, 2 represents a suitable base, 3 is a driving pinion mounted on a shaft 4 that is driven through a disk 5 from a driving rod connection 6 which extends to the source of motive power, not shown.

The pinion 3 meshes with a large driving gear 7 which has the usual connection with a winding drum from which a cable 8 extends to the boom and excavating bucket or scoop, not shown. The winding drum is provided with a brake-drum 9 and a brake-

45 band 10 is arranged to encircle this drum and frictionally engage it when the mechanism for tightening or loosening the band indicated at 11 is operated.

50 The clutch mechanism between the gear

wheel and the drum is of the conventional type and comprises the shoes 9' adapted to engage the internal friction surface provided on the brake drum 9 being normally held out of engagement with such surface by the tension of springs 9''. Links 10' connect these shoes with a hub 10'' that is slidable on the shaft of the drum.

All this apparatus above described is common to hoisting mechanisms and is described merely for the purpose of illustrating the use and operation of my invention.

A bracket 12 is secured to the base 2. A shaft 13 has bearings at one end in said bracket and in a suitable support 14 provided on said base at the other end of said shaft. 70 A hub 15 is mounted on said shaft and has a pinion 16 normally meshing with the teeth of the gear 7 to be operated thereby, and a similar pinion 17 meshes with a gear 18 mounted on a hub 19 which is rotatably 75 mounted on a shaft 20 carried by a yoke 21 that is journaled on the shaft 13 and is free to oscillate thereon. A friction wheel 22 is mounted on the hub 19 in position to engage the friction surface of the brake-drum 9, 80 said wheel being driven from the pinion 17 and operates on the brake-drum to revolve the drum and gear backwardly and cause the cable to become slack without depending upon the weight of the excavating bucket. If 85 a suitable oscillation or swing is imparted to the bucket by the boom and the cable unwound and released at the right time, the bucket may be cast outwardly a considerable distance in much the same way as the bait 90 and hook is cast by the release of a fishing reel. At such time of course the winding drum will be disengaged from the large gear and through this large gear the pinions and the friction wheel will be driven to effect a 95 reverse motion of the winding drum and the unwinding and delivery of the cable.

The friction wheel and yoke 21 are preferably operated by the following mechanism: 100 23 represents a shaft having an arm 24 pivotally connected by a link 25 with the yoke 21. A treadle arm 26 having a foot-engaging pedal 27 is connected with the shaft 23 and is yieldingly held in normal position by a spring 28. When this arm is depressed by the pressure of the foot of the operator, the yoke and friction wheel will be raised to engage the wheel with the surface of the brake- 105

2
drum and as this wheel is driven through its pinion connection with the large gear 7, a backward movement of the winding drum will immediately be effected and this will continue as long as the friction wheel is in contact with the surface of the brake-drum. As soon as the operator removes his foot from the pedal, the spring 28 will raise the arm 26, withdraw the friction wheel from contact with the drum and allow the winding drum to become stationary or it may be connected again with the large gear and the winding operation resumed. By this simple attachment to the winding mechanism of a hoisting apparatus I am able to unwind or remove the cable from the drum much more rapidly than has been possible heretofore and deliver the bucket or scoop at the work a considerable distance from the end of the supporting boom.

I claim as my invention:

1. A hoisting apparatus comprising a winding drum and cable therefor, said drum having an annular friction surface, means for revolving said drum in one direction to wind the cable thereon, said drum being temporarily disconnected from said revolving means to allow backward movement, and a friction wheel engaging said winding drum friction surface for accelerating its backward movement to hasten the discharge of the cable from the drum, an oscillating element supporting said wheel, a pinion carried by said element and connected to said wheel, and means for oscillating said element and connecting said pinion with said revolving means.

2. A hoisting apparatus comprising a winding drum and cable therefor, and means for

revolving said drum to wind the cable thereon, said means comprising a driving pinion and gear, said drum being disconnected from said gear to allow backward movement of the drum, a pinion meshing with said gear to be driven thereby, an oscillating yoke, a friction wheel carried by said yoke and adapted to engage an annular friction surface provided on said drum, said friction wheel having a driving connection with said pinion and adapted to accelerate the backward movement of said drum to unwind said cable, and means within control of the operator for oscillating said yoke to engage said wheel with said friction surface.

3. A drum having a friction surface, a driving gear, a clutch for connecting the gear with the drum, a shaft, a yoke swingable on the shaft, said yoke having a friction wheel journaled thereon and engageable with the friction surface and carrying a gear, a duplex gear on the shaft, connecting the driving and friction wheel gears, and means for controlling swinging motions of the yoke.

4. A hoisting apparatus comprising a winding drum, a driving gear therefor, a clutch mechanism for causing gear and drum to rotate in unison a yoke swingably mounted and having a friction wheel engageable to drive the drum, said friction wheel having a gear, and gearing rotatable on an axis common to the yoke, said gearing arranged to drive the wheel, and to be driven by the drum gear when the yoke is swung toward the drum.

In witness whereof, I have hereunto set my hand this 23rd day of June, 1924.

WILLIAM SOMMER.
